UNITED STATES PATENT OFFICE

155,622

DESIGN FOR A RAILWAY CAR BODY

Frank L. Murphy and James E. Candlin, Jr., Chicago, Ill., assignors to Pullman-Standard Car Manufacturing Company, Chicago, Ill., a corporation of Delaware

Application November 28, 1947, Serial No. 142,866

Term of patent 14 years

(Cl. D66—1)

To all whom it may concern:

Be it known that we, Frank L. Murphy and James E. Candlin, Jr., citizens of the United States of America, and residents, respectively, of Chicago, county of Cook, and State of Illinois, have invented a new, original, and ornamental Design for a Railway Car Body, of which the following is a specification, reference being had to the accompanying drawings, forming part thereof.

The characteristic features of the present design reside in the bedroom interior design shown in the drawings, in which

Fig. 1 is a general perspective view of a conventional railway car body of the type in which our new design is incorporated and having portions broken away to reveal the arrangement of the double bedroom within the body, and indicating the supporting trucks in dotted lines for purely illustrative purposes;

Fig. 2 is a general perspective view of our new design of bedroom in the railway car body, and having portions broken away to afford a better illustration of the interior;

Fig. 3 is a horizontal mid-sectional view taken through the bedroom;

Fig. 4 is a vertical longitudinal section taken through the room and showing the door side of the room;

Fig. 5 also is a vertical longitudinal section taken through the room but showing the window side of the room;

Fig. 6 is a vertical transverse sectional view showing one of the opposite ends of the room;

Fig. 7 also is a vertical transverse sectional view but showing one side of the intermediate folding and sliding wall in the room; and

Fig. 8 is a vertical transverse sectional view similar to Fig. 7 but showing the opposite side of the intermediate wall.

We claim:

The ornamental design for a railway car body, substantially as shown and described.

FRANK L. MURPHY.

JAMES E. CANDLIN, JR.
